(57) **CLAIM**

The ornamental design for a combination box and lid, as shown and described.

DESCRIPTION

FIG. 1 is a front elevational view of a first embodiment of a combination box and lid according to my design, the lid covering an upper opening of the box,

FIG. 2 is a side elevational view thereof, the opposite side view being a mirror image,

FIG. 3 is a top perspective view thereof,

FIG. 4 is another top perspective view thereof similar to FIG. 3 wherein the lid is moved sideways relative to the box to expose a portion of its upper opening,

FIG. 5 is a top perspective view thereof with the lid reversed in positioning on the box so as to cover a bottom wall thereof,

FIG. 6 is another top perspective view similar to FIG. 5 wherein the lid is moved sideways relative to the box,

FIG. 7 is a front elevational view of a second embodiment of a combination box and lid according to my design, the lid covering an upper opening of the box,

FIG. 8 is a side elevational view thereof, the opposite side view being a mirror image,

FIG. 9 is a top perspective view thereof,

FIG. 10 is a top perspective view thereof similar to FIG. 9 wherein the lid is moved sideways relative to the box to expose a portion of its upper opening,

FIG. 11 is a top perspective view thereof with the lid reversed in positioning on the box so as to cover its bottom wall,

FIG. 12 is a top perspective view similar to FIG. 11 wherein the lid is moved sideways relative to the box,

FIG. 13 is a front elevational view of a third embodiment of a combination box and lid according to my new design,

FIG. 14 is a side elevation view thereof, the opposite side view being a mirror image,

FIG. 15 is a top perspective view thereof,

FIG. 16 is another top perspective view similar to FIG. 15 wherein the lid is moved sideways relative to the box to expose a portion of its upper opening,

FIG. 17 is a top perspective view thereof with the lid reversed in positioning on the box to cover its bottom wall; and,

FIG. 18 is a top perspective view similar to FIG. 17 wherein the lid is moved sideways relative to the box.
